M. W. SCHLOSS,
GIRDLE,
APPLICATION FILED APR. 10, 1917.

Patented July 8, 1919.

Meyer W. Schloss ^{INVENTOR}
BY
Rosenbaum, Stockmeyer & Borst ^{ATTORNEY}

UNITED STATES PATENT OFFICE.

MEYER W. SCHLOSS, OF NEW YORK, N. Y., ASSIGNOR TO TREO COMPANY, INC., A CORPORATION OF NEW YORK.

GIRDLE.

Specification of Letters Patent.

Patented July 8, 1919.

1,308,870.

Application filed April 10, 1917. Serial No. 160,915.

To all whom it may concern:

Be it known that I, MEYER W. SCHLOSS, a citizen of the United States, residing at the city of New York, in the borough of 5 Manhattan and State of New York, have invented certain new and useful Improvements in Girdles, of which the following is a full, clear, and exact description.

This invention relates to girdles intended 10 to be worn in the place of corsets, the objects being, first, to provide a construction for such an article of apparel which avoids the use of the busks and fastening hooks commonly utilized heretofore; second, which is 15 constructed to give the "straight front" effect now in vogue; and, third, to provide an elastic structure, the tension of which, when on the body, may be adjusted to suit.

In the accompanying drawing, the complete 20 girdle is shown in one perspective view. The girdle comprises a band of elastic webbing A which will ordinarily be ten or more inches in width, and of a length to approximately fit around the body covering 25 more or less of the region above and below the waist line. This band is perfectly flat when laid out straight, it being without gores or darts and otherwise unshaped to the figure. The band may be made up of a series 30 of longitudinal elastic ribbons or narrow bands a sewed together edge to edge at a', and preferably the band is provided in the upper part at or slightly below the upper edge with a narrow band or zone b of webbing which is also elastic, but being of a 35 less yielding nature than the main body A. This zone b is intended to be located at the waist line when the garment is worn. The extremities of the band are respectively provided 40 with rows of eyelets c and are to be connected together by means of a lacing d, which is threaded through the eyelets in the usual manner of applying lacings to corsets. The front of the band is completely and permanently 45 closed, but is provided with a shield or pad e of inelastic material, such as cotton goods or any other suitable material. This shield is provided with a number of vertically arranged parallel pockets f in 50 each of which is placed a bone or steel designed to afford a suitable amount of stiffen-

ing to the front of the girdle to produce the effect, when the garment is worn, of a straight front, viz, a front which does not curve outward above or below the waist line. 55 This straight front effect is more pronounced by reason of the absence of any opening at the front.

The lacings are supposed to be permanently in place and they may be substituted 60 by any equivalent device, such as cross straps, which may be taken up or let out at will. The article is donned by first loosening the lacings, then stepping through and drawing it up to the waist line, whereupon 65 the lacings are tightened until the desired tension is put upon the elastic band, and the lacings then tied. The garment thus applied permits the figure to retain a natural 70 shape, except at the front where the straight effect is produced.

Elastic girdles are usually made of a definite size to fit the waist measure and equipped with clasps or hooks which do not allow for any alteration of the waist size. 75 Should a mistake be made in the waist measurement or the girdle become elongated by wear, it is desirable to have means for readjusting the waist size. Lacings are the best means for this purpose and they are also 80 advantageous in that no metal studs or projecting parts accompany their use which often show through the outer garments. By providing a completely closed elastic band equipped at one point with lacings, the figure 85 is given a smooth appearance and the garment can be put on readily in the manner above described by loosening and afterward taking up the lacings. 90

I claim:

A girdle comprising a flat band of elastic webbing provided with a zone at the region of the waist line which is elastic but less yielding than the body of the band, the extremities of the band having co-operating 95 fastening devices and the band midway of its extremities being provided with a flat stiffening pad extending across the said zone.

In witness whereof, I subscribe my signature.

MEYER W. SCHLOSS.
